UNITED STATES PATENT OFFICE.

PETER JAKUBOWSKI, OF CHICAGO, ILLINOIS.

EXTENSIBLE PICTURE FRAME.

Application filed March 6, 1926. Serial No. 92,734.

This invention relates to extensible picture frames and its main object is the provision of a frame composed of a plurality of cooperating frame sections which are adapted to be adjusted in respect of each other to provide a frame which would fit various sizes of pictures.

Another object of the invention is to provide a frame composed of four corner sections where the ends of the adjacent corner sections form the sides of the frame and which are adjustable longitudinally for varying the length of the sides for accommodating pictures of various sizes.

With the above general objects in view and others that will appear as the nature of the invention is better understood, the same consists in the novel construction, combination and arrangement of parts hereinafter more fully described, illustrated in the accompanying drawings and pointed out in the appended claims.

In the drawings forming a part of this application, and in which like designating characters refer to corresponding parts throughout the several views,

Fig. 1 is a front elevational view of the frame constructed in accordance with the present invention;

Fig. 2 is a rear elevational view of the frame;

Fig. 3 is a side view of the frame partly in section and partly in elevation, taken on line 3—3 of Fig. 2;

Fig. 4 is an elevational view of frame support;

Fig. 5 is a cross-sectional view of the support taken on line 5—5 of Fig. 4, looking downwardly;

Fig. 6 is a face view of a blank out of which corner sections are constructed by suitably forming the blank;

Fig. 7 is a front elevational view of one corner section and of the ends of two adjacent corner sections illustrating the cooperation between the corner sections of the frame;

Fig. 8 is a sectional view through two cooperating ends of adjacent corner sections, the view being on line 8—8 of Fig. 7;

Fig. 9 is a similar view on line 9—9 of Fig. 7; and

Fig. 10 are perspective views of a loop

or keeper at each end of several corner sections, illustrating the formation of the loop 55 or keeper.

The frame embodies four L-shaped sections, 11, 12, 13 and 14, each constructed of a like blank illustrated on Fig. 6. Said blank when suitably formed will provide a 60 face 15 and flanges 16 and 17, which flanges in cooperation with flanges of the remaining corner sections will make sides of the frame as is apparent. Each of said flanges 16 and 17 is provided at its outer termination with 65 integrally formed strips 18 for the purpose hereinafter mentioned.

Referring to Fig. 1 the upright portions of corner sections 11 and 12 with their respective faces 15 and sides 16, are positioned 70 within the corresponding ends of corner sections 13 and 14 in the assembled state of the frame as is clearly apparent from Figs. 7, 8 and 9. This telescopic arrangement of said ends permits the upright extension of the 75 frame. A similar arrangement is made for extension of the frame on horizontal line, where the horizontal ends of corner sections 11 and 13 are received within the corresponding ends of corner sections 12 and 14, so that 80 the first mentioned ends are adapted for sliding movement within the latter ends.

To permit the reception of the upright ends of corner sections 11 and 12 within the corresponding ends of sections 13 and 14, 85 and the horizontal ends of sections 11 and 13 within the corresponding ends of sections 12 and 14 as hereinabove stated, the strips 18 are maintained in the upright condition 90 illustrated in the first position of Fig. 10. When all the ends of the corner sections are 95 in a cooperative arrangement hereinabove mentioned strips 18 of both ends of corner sections 11 and 14 are bent horizontally toward the center of the frame, as illustrated in the second position of Fig. 10, thus forming an L-shaped slot 19 for accommodating the side 16 and face 17 of the ends of corner sections 12 and 13. Thereupon 100 said strips 18 of corner sections 11 and 14 are bent downwardly and then in the reverse direction from that shown on second position of Fig. 10 until position 20 of strips 18 shall abut the inner faces of the ends of corner sections 11 and 14 and shall terminate 105 in a downwardly depending lip 21 abutting

the inner faces of sides 16 and 17 of corner sections 11 and 14, all as illustrated on Fig. 8 and in the third position of Fig. 10.

From the hereinabove description it will be apparent that said strips 18 when bent will form loops wherein the ends of corner sections 12 and 13 will be adapted to make longitudinal sliding movement, horizontally and vertically, as the case may be.

10 Referring to Fig. 9 strips 18 of the corner sections 12 and 13 loop around the ends of sections 11 and 14. Here, however, the strips 18 are bent in the reverse direction, the inner ends thereof abutting the inner 15 faces of the ends of corner sections 11 and 14, then passing over the upper faces 15 of sections 12 and 13 and then terminating in downwardly depending lips 22.

10 Referring to Fig. 7 which shows section 11 in operative engagement with the adjacent ends of sections 12 and 13. The relative position of section 14 in respect of 20 the adjacent ends of sections 12 and 13 is similar to the relative position of the section 11 in respect of the adjacent ends of sections 12 and 13, both said sections 11 and 14 being covered at their ends by the adjacent ends of sections 12 and 13.

It is observed that by virtue of the fact that the strips 18, or, in their ultimate formation, the keepers, are integrally formed with each end of the several corner sections 35 they maintain a symmetrical position relative to each other and to the frame no matter to what extent the frame may be adjusted. From the hereinabove description it will be further apparent that the frame 40 may be reduced in size until the keepers 18 bear against the corner sections at their elbows, or extended until the two keepers on either two or four sides of the frame come to bear against each other.

45 The inner horizontal faces or keepers 18 are provided with rectangular supports 23 which are soldered or in any other suitable manner mounted upon each keeper, as shown on Figs. 2 and 3. The outer or rear walls 50 of said supports have leaf springs 24 pivoted thereto by rivets 25. The opposite ends of said springs curve downwardly and bear against picture and glass cover 26 preventing shifting thereof. The springs are 55 adapted for swinging movement on their pivot points. To remove the picture from the frame springs 24 are swung around until they remain in parallel relation with the sides 16 of the frame, the frame is then 60 extended and the picture will then be capable of ready removal.

A pair of opposite supports 23 on the corresponding sides of the frame is provided with an integrally formed lug 27, 65 each having a downwardly projecting flange

28 provided with an aperture as seen on Figs. 2 and 3. Support illustrated on Figs. 4 and 5, by means of flanges 29 angularly projecting from legs 30 is adapted for pivotal mounting on flanges 28 of screws 31 70 for the purpose of supporting the frame, as shown on Fig. 3. Said support is adapted for supporting the frame either horizontally or vertically, depending upon the nature of the picture, as is obvious, and for this purpose the frame is provided with two pairs of lugs 27 and flanges 28, one opposite pair thereof being on a line parallel to the horizontal axis of the frame and the other on the line parallel to the vertical axis thereof. 75

Each leg 30 of the support has a laterally projecting extension 31. The two extensions at their outer ends meet and are coupled by means of keepers 32 to provide an extensible brace for legs 30. Each of said keepers is 80 in a rigid engagement with the end of its respective extension 31 and forms a slot for permitting insertion and sliding movement therewithin of the other extension. Thus the support is capable of extension on horizontal line with the extension of the frame on the same line.

While there is described herein a preferred embodiment of the present invention, it is nevertheless to be understood that minor changes may be made therein without departing from the spirit and scope of the invention as claimed.

What I claim as new is:

1. An extensible picture frame assembly 100 comprising a plurality of sections formed L-shaped in cross-section and adapted to overlap in sliding contact with each other, and each of the respective ends of said sections having integrally formed thereon a lateral elongated strip adapted to be bent to engage about the free surface of the end of the section and the free surface of the adjacent overlapping section whereby to form a keeper to prevent relative disengagement 105 of the sections.

2. Means for forming an extensible picture frame comprising a plurality of sections adapted to overlap in relative sliding contact with each other and each bent angularly in cross-section to form the front and edge faces of the frame and the channeled picture receiving back, and each of the respective ends of each section having integrally formed thereon a lateral elongated strip adapted to be bent to engage about the free surfaces of the overlapping ends to form a keeper having a general cross-sectional configuration similar to that of the sections. 115

3. Means for forming an extensible picture frame assembly comprising a plurality of blanks each having an L-shaped body and a pair of strips extending laterally from the respective ends of the body, said body adapted to be bent to substantially define a right- 120

angle in cross-section, and all of said bodies adapted to be placed together in overlapping relationship to form a picture frame, the respective strips being bent in assembly to 5 engage the free surfaces of adjacent portions of the overlapping bodies to provide keepers to hold said bodies in assembly.

4. A sheet metal construction for extensible picture frames comprising a plurality of 10 L-shaped sheet metal bodies each having lateral end extensions and adapted to be bent to substantially define a right-angle in cross-section, and all of said bodies adapted to be placed together in overlapping relationship 15 to form a rectangular construction constitut-

ing the picture frame, the lateral end extensions adapted to be bent about and in engagement with the free surfaces of adjacent overlapping bodies to form keepers, and a support for the frame comprising sheet 20 metal legs having lateral extensions the ends of which are provided with ears adapted to be bent to engage the adjacent free surfaces of the extensions to form keepers whereby said support for the frame is rendered adjustable simultaneously with the frame and in the same operation. 25

In testimony whereof I affix my signature.

PETER JAKUBOWSKI.
